Primary Examiner — Philip S Hyder(74) *Attorney, Agent, or Firm* — FisherBroyles, LLP;
Craig W. Mueller(57) **CLAIM**

The ornamental design for a replaceable blade, as shown and described.

DESCRIPTION

FIG. 1 is a perspective view of the replaceable blade;
 FIG. 2 is a front elevation view thereof;
 FIG. 3 is a rear elevation view thereof;
 FIG. 4 is a left elevation view thereof;
 FIG. 5 is a right elevation view thereof;
 FIG. 6 is a top plan view thereof; and,
 FIG. 7 is a bottom plan view thereof.
